UNITED STATES PATENT OFFICE

WILLIAM W. GREEN, OF NILES, MICHIGAN.

RAILWAY-TIE.

No. 829,203.

Specification of Letters Patent.

Patented Aug. 21, 1906.

Application filed April 16, 1906. Serial No. 311,867.

To all whom it may concern:

Be it known that I, WILLIAM W. GREEN, a resident of Niles, in the county of Berrien and State of Michigan, have invented certain new and useful Improvements in Railway-Ties, of which the following is a full, clear, and exact description.

My invention relates to certain new and useful improvements in railway-ties; and its object is to produce a tie having great strength and durability and which is easily and cheaply constructed.

To such end the invention consists in certain novel features of construction, a description of which will be found in the following specification and the essential characteristics thereof definitely pointed out in the claims.

The invention is clearly illustrated in the accompanying drawings, in which—

Figure 1 is a cross-section through a tie embodying my invention and showing a rail in position thereon. Fig. 2 is a side view of a portion of the tie, the rail being shown in section. Fig. 3 is a perspective view of the tie alone, and Fig. 4 is a perspective view of a brace used upon the curves of the track.

In its preferred form my improved tie is constructed of a metal casing and a concrete filling, the casing being so constructed as to provide a comparatively wide flanged base, which is embedded in the gravel or other ballast of the road-bed, and a suitably-flanged top, to which the rails may be secured. The casing is preferably formed of two channel members A A, arranged with their flanges a' turned outward and their webs a² spaced apart sufficiently to embrace between them a concrete or other artificial-stone filling B. The two channel members are connected by rivets a³, which are headed upon the outer faces of the webs a². Sleeves a⁴ extend between the webs and surround the rivets and are embedded in the concrete filling. The lower flanges a' are preferably somewhat wider than the flanges a in order that the tie may have considerable width at the base, so that the gravel of the road-bed may obtain the necessary purchase thereon to prevent accidental tipping of the tie when subjected to the heavy loads passing over it. The concrete filling is covered by a plate C, which extends over the edges of the flanges a of the channel members, and said plate has ribs c on its edges, which embrace the flanges a to prevent spreading of the channel members at this point. The plate C is riveted or other-

wise secured to the channel members A, preferably by means of rivets c' passing through the flanges a. A rail is shown at D, and said rail is secured upon the tie by means of bolts d d', which pass through holes in the plate C and flanges a and through spring-clips E, nuts d² being provided upon the threaded ends of the bolts, which bear upon the spring-clips. The heads d³ of the bolts extend at right angles to the bodies thereof and engage with the lower flanges d⁴ of the rail. The spring-clips E are secured upon the under side of the flanges a by means of rail-positioning pins d⁵, the upper ends of which are provided with heads which bear upon the upper surface of the plate C and the lower ends of which extend through the spring-clips and are headed upon the under side thereof. The ends e and middle portion e' of the clips are bent upward and engage the under side of the flanges a, so that the main portions of the spring-clips are slightly separated from the flanges. When the nuts d² are screwed up tight on the bolts d d', the tension of the spring-clips is sufficient to prevent their accidental unscrewing and act as nut-locks therefor. The pins d⁵ are preferably set diagonally opposite each other and spaced apart, so that they will receive the lower flange of the rail between them. There are two pairs of positioning-pins, one pair for each rail, and the two pairs are properly spaced apart, so that when the rails are laid in place between each pair they will be at the correct distance apart and will need no further adjustment. Considerable time and labor is thus saved in building the track, because the rails can be laid in place at once and secured, while ordinarily they have to be spaced apart by accurate measurement, inasmuch as their proper spacing is a matter of greatest importance.

The brace which is usually employed at the curves of the track is shown at F in Fig. 4 and may be riveted or bolted to the tie and so positioned as to bring its upper edge into engagement with the rail.

I realize that various alterations and modifications of the construction shown and described are possible, and I do not, therefore, intend to limit myself to their exact construction.

I claim as new and desire to secure by Letters Patent—

1. In a railway-tie, the combination with a pair of suitably-connected channel mem-

bers, of a concrete filling material between the channel members having the connecting means embedded therein.

2. In a railway-tie, the combination with 5 a pair of channel members, and connecting bolts or rivets, of a concrete filling material between the channel members having the bolts or rivets embedded therein.

3. In a railway-tie, the combination with 10 a pair of channel members arranged with their flanges extending outward, and rivets connecting the webs thereof, of a concrete filling material between the webs having the rivets embedded therein.

15 4. In a railway-tie, the combination with a pair of suitably-connected channel members, of a plate spanning said members and secured thereto, and a concrete filling material between the channel members having the 20 connecting devices embedded therein.

5. In a railway-tie, the combination with a pair of channel members, and a plate spanning said channel members having ribs on its side edges embracing the upper flanges of the 25 channel members, of a concrete filling material between the channel members having connecting devices embedded therein.

6. In a railway-tie, the combination with a pair of channel members having their 30 flanges extending outwardly from the body of the tie, means for spacing the channel members apart and means of connection between them, of a plate spanning said channel members and riveted to the upper flanges

thereof, and a concrete filling material inter- 35 posed between the channel members.

7. In a railway-tie, the combination with a pair of suitably spaced and connected vertical webs having horizontally-extending flanges, of a concrete filling between the webs, 40 a plate spanning said webs and riveted to the flanges, and rail-positioning pins extending up from the plate.

8. In a railway-tie, the combination with a flanged body, of a spring-clip, a rail-spacing 45 pin connecting the clip to the body, a rail-securing bolt passing through the clip, and a nut threaded upon the bolt and engaging the spring-clip.

9. In a railway-tie, the combination with 50 a flanged body, of a pair of spacing-pins having flat vertical faces to embrace the rail, and bolts engaging the rail and adapted to connect the same with the tie.

10. In a railway-tie, the combination with 55 a three-sided casing having outwardly-extending flanges at its upper edge, of a concrete filling material inclosed on three of its sides by said casing.

In witness whereof I have signed the above 60 application for Letters Patent, at Chicago, in the county of Cook and State of Illinois, this 13th day of April, A. D. 1906.

WILLIAM W. GRÉEN.
